UNITED STATES PATENT OFFICE.

GEORGE KALKBRENNER, OF MARION, OHIO.

IDENTIFICATION DEVICE.

1,338,181.

Specification of Letters Patent. Patented Apr. 27, 1920.

Application filed May 15, 1919. Serial No. 297,319.

To all whom it may concern:

Be it known that I, GEORGE KALKBRENNER, a citizen of the United States, residing at Marion, in the county of Marion and State 5 of Ohio, have invented certain new and useful Improvements in Identification Devices, of which the following is a specification.

This invention relates to identification devices, and has particular reference to an 10 improved device of this character capable of being employed in connection with a bunch of keys, so that in the event of the latter being lost or mislaid the finder may readily identify the owner of the keys so that proper 15 restoration can be made.

Another object of the invention resides in an improved structure capable of being connected with a key ring and so constructed as to receive an identification card, said device 20 providing a pocket in which the card is adapted to be inserted and the walls of said pocket being apertured at their ends for the reception of the key ring, whereby when the key ring is in place the removal of the card 25 from said pocket will be prevented.

With these and other objects in view, as will appear as the description proceeds, the invention accordingly consists in the novel 30 features of construction, combination of elements and arrangement of parts hereinafter to be fully described and having the scope thereof defined in the appended claim.

In the accompanying drawing, forming a part of this specification, and in which similar characters of reference denote like and 35 corresponding parts:

Figure 1 is a perspective view of my improved device and illustrating the same attached to a key holding ring,

40 Fig. 2 is a transverse vertical sectional view, and

Fig. 3 is a detail perspective view of the identification card employed in connection with the device.

45 Fig. 4 is a detailed sectional view of a slightly modified form of the invention.

The identification device 1 comprising the preferred form of the invention, consists of a blank of sheet metal, which is formed to 50 provide a tool extremity 2 and a combined pocket and handle extremity 3. To form the extremity 3 the blank is bent upon itself so that its edges will terminate contiguously as at 4, whereby spaced side walls 5 are provided, a pocket 6 being formed between said side walls. The extremity 2 of

the device is in this instance in the form of a cap remover for bottles and by the addition of this tool the utility of the device 1 is materially broadened, however, it will 60 be appreciated that the form of the extremity 2 may be widely varied so that other forms of instruments may be provided instead of the form shown or, in the final analysis, the presence of the extremity 65 2 may be eliminated. The end of the handle 3, adjacent to the extremity 2, is closed when the opposite end is left open, as at 7, to permit of the insertion of an identification card 8 into the pocket 6, after which operation said end 7 may be closed if desired. To retain the card 8 in position within the pocket 6 and to prevent its accidental removal therefrom registering openings 9 are 70 formed in the extremity 3 at points contiguous to the open end 7 thereof, and these openings 9 are adapted to receive a key ring 75 10, or an equivalent structure.

It will thus be manifest that when attached to the ring 10 the device 1 will form a part 80 thereof, and by inserting the ring through the openings 9 the escape of the card 8 from the pocket 6 is effectively prevented. However, if the device is lost, the finder simply removes the device from its position upon the ring, thereby permitting the card 8 to be withdrawn from the device 1 85 so that its indicia, relative to its owner, may be readily viewed. Instructions are preferably stamped or printed upon the 90 outer face of one of the side walls 5 of the device so that a finder will encounter no difficulty in determining the location of the card 8 and its manner of removal. An auxiliary opening 11 is formed in one or both 95 of the walls 5 to permit of the insertion of a sharp pointed tool, which latter may be employed in facilitating the removal of the card 8 from its position within said pocket. The opening 11 is preferably of square 100 formation and it usefully serves in the capacity of a socket wrench.

From the foregoing description it will be seen that there is provided a simple and useful device for the purposes above set 105 forth, and one which will be cheap to manufacture and capable of extensive use as an advertising novelty. If desired, the material from which the openings 9 are formed may be bent over to provide a prong 12, 110 which is capable of obstructing the open end of a pocket 6 to prevent removal of the

card 8 in substantially the manner as is performed by the ring 10.

What I claim is:

An identifying attachment for key rings comprising a substantially inclosed body having a pocket formed therein, an identifying card capable of being positioned within said pocket, said body being open at one end to permit of the longitudinal insertion of said

card into the pocket, and the walls of said body contiguous to the open end of the latter being apertured for the reception of a key ring, whereby when the attachment is carried by the key ring, the open end of said pocket will be closed by said ring to effect the retention of said card therein.

In testimony whereof I affix my signature.

GEORGE KALKBRENNER.
